(57) CLAIM

The ornamental design for a female urine specimen cup, as shown and described.

DESCRIPTION

FIG. 1 is a top and front perspective view of a female urine specimen cup showing my new design;

FIG. 2 is a front view thereof shown at a reduced scale, the unshown rear view being of identical appearance;

FIG. 3 is a top plan view thereof shown at a reduced scale;

FIG. 4 is an end view thereof shown at a reduced scale, the opposite end view being of identical appearance; and,

FIG. 5 is a bottom view thereof shown at a reduced scale.
